SHOE FORM

William J. De Witt, Auburn, N. Y., assignor to
Shoe Form Co., Inc., Auburn, N. Y., a corpora-
tion of New York

Application January 19, 1933, Serial No. 652,463

17 Claims. (Cl. 12—128.1)

This invention relates to an improvement in shoe forms and more particularly to an improvement in a form of the general type shown and described in my Patent No. 1,874,923, dated 5 August 30, 1932 and in my copending application Serial No. 549,186, filed July 7, 1931.

The primary object of this invention is to provide in a shoe form having a two part cross brace means for positively actuating the cross brace 10 in one direction and for yieldably actuating it in the opposite direction; as for example actuating the cross brace yieldably in one direction to expand the walls of the form and positively in the opposite direction to contract the walls 15 of the form and facilitate its removal from a shoe.

Other objects will appear from a consideration of the following description of one embodiment of this invention and of the drawing which forms a part thereof and in which

20 Fig. 1 is a side elevation of a shoe form embodying this invention;

Fig. 2 is a bottom plan view thereof on a larger scale showing the form in an intermediate position in full lines and in the fully expanded position in dotted lines;

25 Fig. 3 is a view similar to Fig. 2 showing the form in the fully contracted position;

Fig. 4 is a sectional view, taken along the line 4—4 of Fig. 2, of a detail of construction;

30 Fig. 5 is a view similar to Fig. 4 of another embodiment of the invention; and

Figs. 6 and 7 illustrate portions of back part members and the manner of treating them.

The shoe form comprises a toe portion 10 having 35 side walls 11 which terminate in flanges 12 joined by a cross brace 13 and a back part member 14 connected at its forward end to the cross brace 13.

The cross brace 13 consists of two sections 15 40 and 16 pivotally joined at their inner ends by a button or rivet 17. The outer end of the section 15 is pivoted to one flange 12 by a button or rivet 18 while the outer part of the section 16 carries a button or rivet 19 which is received and travels in an arcuate slot 20 in the other flange 12. An extension from the inner end of the section 15 terminates in an upwardly projecting tongue 21 having an aperture 22 therein. The sections are movable toward and from the position of alignment shown in Fig. 2 and are stopped thereat by the tongue 21 which contacts with the section 16. (See Fig. 4.)

The back part member 14 comprises a rod or wire 25 covered throughout most of its length by 45 a tube 26 of celluloid or the like. The forward

end of the wire passes through the aperture 22 of the tongue 21 and is headed at its tip, as by the eye 27, to prevent its unwanted separation from the tongue. Surrounding the portion of the wire 25 between the forward end of the tube 26 and the tongue 21 is a coiled spring 28. The rearward end of the back part member 14 terminates in a loop 29 which, if the member be of sufficient length, bears against the heel counter 30 of a shoe. The back part member may, as is 10 well known in the trade be so short that the loop 29 rests upon the insole of the shoe as shown in the drawing of the copending application above mentioned.

The normal position of the shoe form is shown 15 in full lines in Fig. 2 with the sections 15 and 16 in alignment and the button 19 at the rearward end of the slot 20. When the form is to be inserted into a shoe the back part member is retracted to break the alignment of the cross 20 brace sections so that the form assumes the position shown in Fig. 3. After the form has been inserted in the shoe the back part member is advanced and the spring 28 bearing against the tongue 21 moves the sections into alignment and 25 then swings the cross brace as a unit toward the position shown in dotted lines in Fig. 2 until the pressure of the walls of the shoe toe compress the spring and prevent any further free expansion of the toe portion thus indicating that the 30 desired expansion of the toe member has been reached. If the back part member be long enough the loop 29 is placed against the counter 30 and the spring 28 thus acts yieldably to hold both the walls of the toe portion against the walls 35 of the shoe toe and also the loop 29 against the counter 30. When the form is to be removed from the shoe the back part member is retracted to contract the toe portion by swinging the brace and moving the sections out of alignment and 40 to withdraw the form from the shoe. From the foregoing it is apparent that the cross brace is moved positively by the contact of the eye 27 with the tongue 21 when the back part member is retracted and is moved yieldably by the contact 45 of the spring 28 with the tongue 21 when the back part member is advanced.

When the form is inserted in a shoe the only portion exposed is the tube of the back part member and there has been a tendency to make 50 this of celluloid or other material having a single color which may be similar to or a contrast to that of the shoe. I have found it possible as shown in the drawing to make the tube of two or more colors. In Fig. 6 the tube 31 is made of 55

black celluloid and around it is wound spirally a narrow strip 32 of white celluloid which is secured to the tube by the use of a suitable celluloid cement such as acetone. In Fig. 7 the tube 32 is also made of black celluloid around which two narrow strips 33 and 34 of different colors are wound spirally and secured by cement to the tube.

Fig. 5 illustrates another embodiment of the invention wherein the back part member 14 positively engages section 16 of the cross brace and yieldably engages section 15. As there shown the forward end of the wire 25, passed through the aperture 22, engages a tongue 35 which projects upwardly from section 16 having, as here shown, an aperture 36. The end of the wire is passed through the aperture 36 and headed as by an eye 37. When the back part member is advanced the spring 23 bears against the tongue 21 thus, as in the embodiment previously described, compressing the spring and yieldably moving the sections into alignment to expand the toe portion. When the member is retracted the eye 37 contacts with the tongue 35 whereby the brace is positively swung as a unit and the sections are positively moved out of alignment and the form is positively withdrawn from the shoe.

While certain embodiments of the invention have been shown and described I am not limited thereto since other embodiments may be made without departing from the spirit and scope of the invention as set forth in the following claims.

I claim:

1. A shoe form comprising a hollow toe portion having side walls, a cross brace connecting said walls and consisting of sections movable toward and away from a position of alignment to expand or contract the walls of the toe portion, tongues projecting from the inner end of each cross brace section and having apertures therein and a back part member comprising a wire the forward end of which is passed through the apertures in both said tongues and headed, the headed end of the member acting upon one of said tongues to move the sections positively away from the position of alignment when the member is retracted, and a spring surrounding said wire and bearing against the other tongue to move said sections yieldably toward such position when the member is advanced, the wire moving forwardly through said apertures.

2. A shoe form comprising a hollow toe portion having side walls, a cross brace connecting said walls and consisting of sections movable toward and away from a position of alignment to expand or contract the walls of the toe portion, tongues projecting from the inner end of each cross brace section and having apertures therein, and a back part member comprising a wire the forward end of which is passed through the aperture in one of said tongues and headed, the headed end of the member acting upon one of said tongues to move the sections positively away from the position of alignment when the member is moved in one direction and a spring surrounding said wire and bearing against the other tongue to move said sections yieldably toward such position when the member is moved in the other direction.

3. A shoe form comprising a hollow toe portion having side walls, a cross brace connecting said walls and consisting of sections movable toward and away from a position of alignment to expand or contract the walls of the toe portion, and a back part member attached to one only of said sections by which the sections are yieldably moved

in one direction and are positively moved in the other direction.

4. A shoe form comprising a hollow toe portion having side walls, a cross brace connecting said walls and consisting of sections movable toward and away from a position of alignment to expand or contract the walls of the toe portion, and a back part member attached to one only of said sections by which the sections are yieldably moved toward the position of alignment and are positively moved away from such position.

5. A shoe form comprising a hollow toe portion having side walls, a cross brace connecting said walls and consisting of sections movable toward and away from a position of alignment to expand or contract the walls of the toe portion, and a back part member attached to one only of said sections, said member comprising a wire by which the sections are positively moved in one direction and a spring by which the sections are yieldably moved in the other direction.

6. A shoe form comprising a hollow toe portion having side walls, a cross brace connecting said walls and consisting of sections movable toward and away from a position of alignment to expand or contract the walls of the toe portion, and a back part member attached to one only of said sections, said member comprising a wire by which the sections are positively moved away from the position of alignment and a spring by which the sections are yieldably moved toward such position.

7. A shoe form comprising a hollow toe portion having side walls, a cross brace connecting said walls and consisting of sections movable toward and away from a position of alignment to expand or contract the walls of the toe portion, and a back part member attached to one only of said sections, said member comprising a wire by which the sections are positively moved in one direction and a spring surrounding said wire by which the sections are yieldably moved in the other direction.

8. A shoe form comprising a hollow toe portion having side walls, a cross brace connecting said walls and consisting of sections movable toward and away from a position of alignment to expand or contract the walls of the toe portion, and a back part member attached to one only of said sections, said member comprising a wire by which the sections are positively moved away from the position of alignment and a spring surrounding said wire by which the sections are yieldably moved toward such position.

9. A shoe form comprising a hollow toe portion having side walls, a cross brace connecting said walls and consisting of sections movable toward and away from a position of alignment to expand or contract the walls of the toe portion, and a back part member attached to one only of said sections, said member comprising a wire by which the sections are positively moved away from the position of alignment, a tube surrounding said wire and spaced from said cross brace, and a spring in the space between the tube and the cross brace by which the sections are yieldably moved toward such position.

10. A shoe form comprising a hollow toe portion having side walls, a cross brace connecting said walls and consisting of sections movable toward and away from a position of alignment to expand or contract the walls of the toe portion, and a back part member attached to one only of said sections, said member comprising a wire by which the sections are positively moved

away from the position of alignment, a tube surrounding said wire and spaced from said cross brace and a spring in the space between the tube and the cross brace and surrounding the wire by which the sections are yieldably moved toward such position.

11. A shoe form comprising a hollow toe portion having side walls, a cross brace connecting said walls and consisting of sections movable toward and away from a position of alignment to expand or contract the walls of the toe portion, and a back part member attached to one of said sections, said member comprising a wire by which the sections are positively moved away from the position of alignment, a tube surrounding said wire and spaced from said cross brace, and a spring in the space between the tube and the cross brace, the rearward end of said member bearing against the heel counter of a shoe in which the shoe form is placed and said spring yieldably moving the sections toward such position of alignment and yieldably holding the rearward end of the member in contact with said heel counter.

12. A shoe form comprising a hollow toe portion having side walls, a cross brace connecting said walls and consisting of sections movable toward and away from a position of alignment to expand or contract the walls of the toe portion, and a back part member attached to one of said sections, said member comprising a wire by which the sections are positively moved away from the position of alignment, a tube surrounding said wire and spaced from said cross brace, and a spring in the space between the tube and the cross brace, and surrounding the wire, the rearward end of said member bearing against the heel counter of a shoe in which the shoe form is placed and said spring yieldably moving the sections toward such position of alignment and yieldably holding the rearward end of the member in contact with said heel counter.

13. A shoe form comprising a hollow toe portion having side walls, a cross brace connecting said walls and consisting of sections movable toward and away from a position of alignment to expand or contract the walls of the toe portion, a tongue projecting from one of said sections and having an aperture therein, and a back part member comprising a wire the forward end of which is passed through the aperture in said tongue and headed, by which the sections are positively moved away from the position of alignment when the member is retracted and a spring surrounding said wire and bearing against said tongue by which the sections are yieldably moved toward such position, when the member is advanced the wire moving forwardly through said aperture.

14. A shoe form comprising a hollow toe portion having side walls, a cross brace connecting said walls and consisting of sections movable toward and away from a position of alignment to expand or contract the walls of the toe portion, a tongue projecting from one of said sections and having an aperture therein, and a back part member comprising a wire the forward end of which is passed through the aperture in said tongue and headed, by which the sections are

positively moved away from the position of alignment, a tube surrounding part of the wire and spaced from the tongue, and a spring surrounding the wire between the tube and the tongue by which the sections are yieldably moved toward such position.

15. A shoe form comprising a hollow toe portion having side walls which terminate in ball flanges one of said flanges having a slot therein, a cross brace connecting said flanges and consisting of two sections pivotally joined at the inner ends, the outer end of one section being pivoted to the unslotted flange and a button carried by the outer end of the other section and movable in the slot of the other flange, said sections being relatively movable toward and away from a position of alignment and said cross brace being movable as a unit guided by said button to expand and contract the toe portion, means for yieldably moving the sections toward the position of alignment and the cross brace as a unit to expand the toe portion and means for positively moving the cross brace as a unit and the sections away from such position to contract the toe portion.

16. A shoe form comprising a hollow toe portion having side walls which terminate in ball flanges one of said flanges having a slot therein, a cross brace connecting said flanges and consisting of two sections pivotally joined at the inner ends, the outer end of one section being pivoted to the unslotted flange and a button carried by the outer end of the other section and movable in the slot of the other flange, said sections being relatively movable toward and away from a position of alignment and said cross brace being movable as a unit guided by said button to expand and contract the toe portion, and a back part member for yieldably moving the sections toward the position of alignment and the cross brace as a unit to expand the toe portion and for positively moving the cross brace as a unit and the sections away from such position to contract the toe portion.

17. A shoe form comprising a hollow toe portion having side walls which terminate in ball flanges one of said flanges having a slot therein, a cross brace connecting said flanges and consisting of two sections pivotally joined at the inner ends, the outer end of one section being pivoted to the unslotted flange and a button carried by the outer end of the other section and movable in the slot of the other flange, said sections being relatively movable toward and away from a position of alignment and said cross brace being movable as a unit guided by said button to expand and contract the toe portion, and a back part member secured to the section of the cross brace pivoted to the unslotted flange, said member comprising a wire by which the cross brace as a unit is positively moved and the sections are positively moved away from the position of alignment to contract the toe portion, and a spring by which the sections are yieldably moved toward the position of alignment and the cross brace is yieldably moved to expand the toe portion.

WILLIAM J. DE WITT.
